[57] CLAIM

The ornamental design for a double-lined mitten as shown and described.

DESCRIPTION

FIG. 1 is a perspective view from the back thumb side of a right-hand mitten with the zipper portion open to reveal the inner lining;

FIG. 2 is a top plan view of the back side of the mitten of FIG. 1;

FIG. 3 is an end view of the mitten from the entrance side thereof;

FIG. 4 is a palm-side view of the mitten.

The characteristic feature of my design resides in the combination of the elasticized wrist and cuff with a zipper on the back of the mitten.
